(57) **CLAIM**

The ornamental design for a smartphone and tablet stand, as shown and described.

DESCRIPTION

FIG. 1 is a front elevation view of a smartphone and tablet stand, showing my new design, wherein the cradle of the stand is oriented at an angle;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a top, front, left perspective view thereof;

FIG. 8 is a top, rear, right perspective view thereof; and,

FIG. 9 is a bottom, rear, left perspective view thereof.

The broken lines illustrate features that form no part of the claimed design.
